UNITED STATES PATENT OFFICE.

HENRY JOHN FORST, OF LOUISVILLE, KENTUCKY.

GRAIN-DOOR FOR BOX-CARS.

No. 862,628.

Specification of Letters Patent.

Patented Aug. 6, 1907.

Application filed February 1, 1907. Serial No. 365,302.

To all whom it may concern:

Be it known that I, HENRY JOHN FORST, a citizen of the United States, residing at Louisville, in the county of Jefferson and State of Kentucky, have invented a 5 new and useful Grain-Door for Box-Cars, of which the following is a specification.

This invention relates to doors for box-cars that may be brought into use when the cars are used for grain and may be folded up and swung out of the way when 10 the cars are to be used for other purposes; and the objects of my improvement are comparative inexpensiveness of manufacture, durability facility in use, simplicity of construction, and to provide a door of this class that may be easily opened and will not stick by 15 reason of the grain working between the joints, that will not leak grain, and that is perfectly secure against bursting out. These objects I attain by means of the mechanism illustrated in the accompanying drawings, in which—

20 Figure 1 is a front elevation of the door closed; Fig. 2 is a front elevation of the door with the lower section open; Fig. 3, a detail of the lock; Fig. 4, a sectional detail of the lock on line A B of Fig. 3; Fig. 5, a vertical section of the door closed; Fig. 6, a transverse section 25 of the door open, folded, and hung from the roof of the car; Fig. 7, an inside or rear elevation of the door closed.

Similar reference characters refer to similar parts throughout the several views of the drawings.
30 The body of the invention consists of sections 1, 2, and 3 of the door, which extends a suitable height for the purpose of holding grain in the car in the usual way, but does not close the entire opening. The upper section 1, and the middle section 2 are made of sufficient length to extend across the opening and lie against the inner face of the door-posts 23. The lower section 3 is of such a length as to pass freely between the adjacent faces of the door-posts 23, leaving the inner faces of the posts exposed. Sections 1 and 2 do not extend entirely 35 across the inner faces of the door posts 23, and the outer edges which are not covered by the sections are faced with pieces 22 which are of approximately the same thickness as the sections of the door where they come in contact with the ends of the sections, and are tapered 40 off from the door. At section 3, the facing pieces 22 are broader than above and cover the entire inner faces of the posts. Pieces 22 form end braces for the door sections, and also serve as guards to prevent grain from getting behind the door sections. The entire 45 door is adapted to swing inward, being hung on hinges 14. The free leaves of the hinges are made of sufficient length to extend some distance across the upper section 1 of the door and are rigidly secured thereto. The free leaves are offset at their pivots so that they extend 50 straight upward, leaving a clear space between them and the inner face of the doorposts in which a board

may be inserted over section 1 to close up the remaining open space when deemed necessary. Sections 1 and 2 are joined together at their meeting edges by means of ordinary strap hinges 18 placed on the battens 4 on 60 the inside of the door. This arrangement adapts section 2 for swinging inward relative to section 1 for the purpose hereinafter described. Sections 2 and 3 are joined together at their edges, by ordinary strap hinges 19 placed on the outside of the door, adapting section 65 3 to swing outward for the purpose hereinafter described.

To prevent section 3 from swinging outward when the car is loaded with grain, cleats 7 are provided, to bear against its entire width, and pivoted at their upper 70 ends on bolts 13, so that the lower ends of the cleats may be free to swing outward. Bolts 13 are disposed just above the line of hinges 19, so that section 3 may swing out freely when the cleats 7 are released and free 75 to swing out.

Bolts 10 are placed near the lower ends of door-posts 23 and let into the surface of the posts so that they are flush with the outside of the car and will not interfere with the passage of the outer car door. Each bolt 10 is provided at its free end with a right-angular hook 80 portion 8 and at its opposite end with a similar right-angular hook portion 9. The two right-angular hook portions of the bolt extend at an angle of 90° relative to each other. Bolt 10 is secured by means of double plates consisting of an outer plate 11 and an inner plate 85 12 which has a groove 21 formed in it to accommodate the bolt. The inner plate 12 is shorter than the outer plate 11, but is brought out flush with the outer edge of plate 11. The inner hook portion 8 of bolt 10 strikes against the rear edge of plate 11 when the bolt is shot 90 out into full operative position. When hook-portion 8 is turned inward into contact with the exposed face of cleat 7 (Fig. 3), the portion 9 extends downward and presses against the inner side of outer plate 11 below the axis of the bolt, so that its rotary motion is limited and stopped when part 8 extends across cleat 7 at right angles thereto. When the bolt is drawn back to release cleat 7, part 8 is turned over through 180 degrees so that it extends outward. Part 9 will now be turned upward and rest against the inner side of plate 11 above 100 the axis of the bolt, and the further rotary motion of the bolt will be stopped. The bolt may now be drawn back so that part 8 recedes into the recess provided therefor in the outer edge of plate 11. It will be understood that the bolt 10 must be shot to the closing 105 position (Fig. 3) before the outer door of the car can be closed. Bolts 10 are also for the purpose of locking cleats 7 in a vertical position against the adjacent faces of door-posts 23.

An eye plate 15, consisting of a plate with a slot in 110 the end, is secured on part 1 of the door, and extends downward so as to lap over part 2 and brace it. When

the door is folded (Fig. 6) the eye in plate 15 is exposed. A hook, 17, is swung from the ceiling of the car in such a position as to enter the eye in plate 15 for the purpose of holding the door near the ceiling when 5 not in use.

The operation of my new grain door will now be understood. To use the door, it is swung down across the portal, as shown in Figs. 1, 2, 5, and 7, so that section 3 lies against the inner edges of cleats 7, and sections 10 1 and 2 lie against the inner faces of posts 23. Cleats 7 are pressed in against the ends of section 3 and locked in that position by means of bolts 10. In order to lock the door, bolts 10 are shot across cleats 7, and portions 15 8 turned inward so as to point toward the door. It will be understood that in this position the bolts not only hold cleats 7 firmly against section 3, but the hook parts 8 at the same time hold cleats 7 firmly against the adjacent faces of door-posts 23, so that any leakage, 20 of grain between cleats 7 and the door-posts is prevented. The hook portion 9 of the bolts prevents them from pulling out of their sockets or turning more than a half revolution. Sections 1 and 2 of the door, being longer than section 3, extend across and rest against the inner faces of posts 23. The door is 25 now in a position for loading the car with grain. It will be understood that, as the car is filled the grain will press against section 3, so as to press it firmly against cleats 7, so that no grain can work in between section 3 and cleats 7. Sections 1 and 2 are also pressed 30 firmly against the inner faces of door posts 23, so that the grain cannot get between them, and thus the inward pressure of the grain against the door tends to seal the door and prevent leakage at any point, making a strong, perfectly secure door. When the car is to be 35 unloaded, it is simply necessary to turn bolts 10 a half revolution, so that portions 8 extend outward, and then push bolts 10 back till parts 8 enter the recess in plate 11, so as to release cleats 7. If bolts 10 work hard, they may be driven back with a stone or any 40 available implement. As soon as cleats 7 are released from bolts 10, section 3 is free to swing outward and

will immediately do so on account of the pressure of the grain against it. If section 3 should stick, a slight pull or prying on eye 20 will start it. The grain will now flow out over the entire length of the threshold 45 until all the pressure from the inside is relieved and the entire door is perfectly free. The operator may then push the door in from the outside and enter the car. He now folds sections 2 and 3 inward and up against section 1, the door breaking at hinges 18, and 50 swings the entire door inward and upward on hinges 14 toward the ceiling of the car until it reaches the position shown in Fig. 6. Here it may be secured by inserting the free end of hook 17 in the eye provided in plate 4. The door is now out of the way, and the 55 remaining grain in the car may be easily unloaded, and the car may be used for any other purpose desired, leaving the door ready for use when required. It will be seen that it is not necessary to use any nails to secure the door, thus avoiding the usual injury to cars and 60 therefore rendering them more durable. It will be understood that when bolts 10 are shot into the position shown in Fig. 1, they are flush with the outside surface of the car, and the regular door may be closed without interference. 65

Having thus described my invention so that anyone skilled in the art pertaining thereto may make and use it, I claim—

A grain door for box cars, adapted to swing inward bodily from the threshold to the ceiling of the car, comprising in combination an upper section extending across the door frame, resting against the inner faces of the door posts, and hinged to the top of the door frame in such a manner as to swing inward; a middle section extending across the door frame, resting against the inner faces of the door posts, and hinged to said upper section so as to swing inward relative thereto; and a lower section of such a length as to pass freely between the adjacent faces of the door-posts and hinged to said middle section so as to swing outward relative thereto, substantially as and for the purpose specified. 70 75 80
